METALLIC COLLAR FOR BEVERAGE MAKERS
OR THE LIKE

Jerry E. Wright, Corning, N.Y., assignor to Corning Glass
Works, Corning, N.Y., a corporation of New York

Filed June 20, 1963, Ser. No. 75,453

Term of patent 14 years

(Cl. D44—26)

FIG. 2

FIG. 1

FIG. 3

FIG. 4

FIG. 5

FIG. 1 is a side elevational view of a metallic collar for beverage makers or the like showing my new design;

FIG. 2 is a top plan view;

FIG. 3 is a front elevational view;

FIG. 4 is a rear elevational view; and,

FIG. 5 is a top plan view.

The broken line showing a vessel and handle is for illustrative purposes only.

I claim:

The ornamental design for a metallic collar for beverage makers or the like, as shown and described.
